UNITED STATES PATENT OFFICE.

PETER S. LARSON AND RANDOLPH C. DUEA, OF SHARON, NORTH DAKOTA.

GRAIN-DOOR FOR BOX-CARS.

No. 867,058.

Specification of Letters Patent.

Patented Sept. 24, 1907.

Application filed May 17, 1906. Serial No. 317,309.

To all whom it may concern:

Be it known that we, PETER S. LARSON and RANDOLPH C. DUEA, citizens of the United States, residing at Sharon, in the county of Steele and State of North Dakota, have invented certain new and useful Improvements in Grain-Doors for Box-Cars; and we do hereby declare the following to be a full, clear, and exact description of the invention, such as will enable others skilled in the art to which it appertains to make 10 and use the same.

Our invention has for its object to provide an improved grain door for box cars, and to this end it consists of the novel devices and combinations of devices hereinafter described and defined in the claims.

15 In the accompanying drawings which illustrate the invention, like characters indicate like parts throughout the several views.

Referring to the drawings, Figure 1 is a view in side elevation, showing the central portion of the body 20 of a box car, having our improved grain doors applied thereto. Fig. 2 is a transverse section taken on the line $x^2 x^2$ of Fig. 1. Fig. 3 is a horizontal section taken on the line $x^3 x^3$ of Fig. 1. Fig. 4 is a vertical section taken on the line $x^4 x^4$ of Fig. 1, showing 25 the parts on an enlarged scale. Fig. 5 is a view taken from the inside of the car body, on an enlarged scale, showing a portion of the door frame and grain door, with some parts broken away and some parts sectioned; and Fig. 6 is a vertical section taken on the line $x^5 x^5$ of 30 Fig. 2.

The numeral 1 indicates a portion of the body of an ordinary box car, the same having, in its sides, the usual door openings 2, to which door openings our improved grain doors 3 are applied.

35 Metallic face plates 4 are secured to each side of the door openings 2 and extend from the top to the bottom of said openings. Each face plate 4 is formed with a guide channel 5 extending from near the top of said plate 4 downward for about two-thirds of the entire 40 length of said plate 4.

The guide channels 5 are, at their tops, curved outward toward the right with respect to Fig. 4, and terminate in seats 6. Said guide channels 5 are, at their bottoms, curved inward toward the left with respect 45 to Fig. 4, and terminate in entrance passages 7. The purpose of said seats 6 and entrance passages 7 will presently appear.

The grain door 3 is provided, at its sides and near its upper edge, with trunnions 8 adapted to work in the 50 guide channels 5. To secure the said door 3 in working position, the trunnions are first inserted within the entrance passages 7 and thence into the guide channels 5.

A pair of lock plates 9 are mounted on said grain door 3 by slot and pin connections 10 for sliding movements 55 toward and from each other. A lever 11 is pivoted near its lower end to the grain door 3 and may be held

in any desired set position by a latch segment 12. A pair of links 13 pivoted one on either side of the pivots of said lever 11 and to the lock plates 9 connect said plates 9 for simultaneous movements in reverse 60 directions. Slots affording lock plate seats 14 adapted to receive the lock plates 9 are formed in the face plates 4 running parallel to the guide grooves 5 and extending from the bottom of said face plates 4 upward for about one-half the entire length of said 65 face plates 4.

As is evident, when the lever 11 is in the position indicated in Fig. 1, the lock plates 9 will be in engagement with the lock plate seats 14. Thus, the grain door 3 is securely held in working position against either 70 outward movements when the car is loaded with grain, or inward when the car is empty. By throwing the lever 11 in a reverse direction from that shown in Fig. 1, the lock plates 9 will be withdrawn from the lock plate seats 14 through the link connections 13, thereby 75 permitting the grain door 3 to swing outward on the trunnions 8, and releasing the load of grain within the car.

To secure the grain door in an idle position, the said door 3 is moved upward, the trunnions 8 sliding in the guide channels 5, until said trunnions 8 enter the seats 80 6. Said door 3 may then be swung up into the position indicated by dotted lines in Fig. 2 and held there by a hook 15. If desirable, a supplemental section 16 may be placed above the grain door 3, which section 16 may be held in working position by the flanged keeper 17. 85

Grain doors of the above character are very efficient for the purposes had in view, as it is very desirable to prevent the door from swinging inward when the cars are empty. Furthermore, the grain doors are of comparatively small cost and may be easily applied to 90 any and all box cars.

What I claim is:

The combination with a car body having a door opening, metallic face plates secured to the opposite sides of said door opening and extending from the top to the bottom 95 thereof and formed with vertical lock plate seats and with vertical guide channels, said seats and channels laterally offset and overlapping one another, and the said channels terminating at their upper ends in seats and terminating at their lower ends in entrance passages, of a grain door having at its upper portion headed trunnions adapted to enter said entrance passages and slide and work pivotally in said guide channels, and to enter said seats for supporting said door in an elevated position, lock plates mounted on the ends of said grain door for movements toward and 100 from each other and adapted to engage the lock plate seats of said face plates, and means for imparting simultaneous movements to said lock plates in reverse directions, substantially as described.

In testimony whereof we affix our signatures in presence 110 of two witnesses.

PETER S. LARSON.
RANDOLPH C. DUEA.
